UNITED STATES PATENT OFFICE.

WILBUR M. GARRETT, OF LOOKEBA, OKLAHOMA.

KAFIR-HEADER.

1,338,295.

Specification of Letters Patent. Patented Apr. 27, 1920.

Application filed August 22, 1919. Serial No. 319,197.

To all whom it may concern:

Be it known that I, WILBUR M. GARRETT, a citizen of the United States, residing at Lookeba, in the county of Caddo and State 5 of Oklahoma, have invented a new and useful Kafir-Header, of which the following is a specification.

This invention relates to machines for heading Kafir corn, sorghum and other fod- 10 der plants in which it is desirable to separate the grain head from the stalk. The object of the invention is to provide a machine that will cut the heads from the stalks and convey each to separate points of de- 15 posit.

Another object is the provision of a novel 20 form of cutting means. Other objects will appear as the description proceeds, it being within the province of the disclosure to im- 25 prove generally and enhance the utility of devices of that class to which the present invention appertains. It is also to be un- derstood that slight changes may be made within the scope of what is claimed without departing from the spirit or sacrificing any 30 of the advantages of the invention.

In the drawing:—

Figure 1 is a side elevation of the ma- 35 chine.

Fig. 2 is a view in central longitudinal section.

Fig. 3 is a plan view partly in section.

Fig. 4 is a transverse sectional view.

Fig. 5 is a detail view of the cutting 40 members.

Referring to the drawings by characters of reference the numeral 1 designates a frame, having corner posts 2, top and bottom side rails 3 and 4 respectively and in- 45 termediate longitudinal beams 5 and 6.

A shaft 7 mounted for rotation at one side of the frame, in bearings carried by the end posts 2, is provided with a drive pulley 8, a balance wheel 9 and a belt wheel 45 10 being mounted on the shaft outside the frame. At the opposite end of the shaft 7 a cutting knife 11 is secured to the said shaft, the knife comprising a circular disk provided with a series of arcuate cutting 50 edges 12 extending about the periphery of the disk. A portion of the disk 11 travels between a pair of concavo-convex disks 13, which are secured to a shaft 14, mounted for rotation at the opposite side of the 55 frame from the shaft 7, the disks being secured to the shaft with their concave faces

adjacent and their outer edges meeting. The disk 11 is inserted between the edges of the disks 13, said edges being sharpened and in contact with the disk 11, an effective 60 cutting device being thus formed. Frictional engagement of the contacting portions of the driven disk 11 with the disks 13 to cause the disks 13 to rotate.

The cutting device is located at one end 65 of the frame 1 and a housing 15 secured to the frame covers the outer edge of the cutter 11 to prevent persons coming in contact therewith, the other member 13 of the cutting device being protected by a guard 70 16 and a feeding table 17, which extends laterally from one of the top rails 3 and practically shields the cutter. A stand 18 is erected at one side of the frame below the feeding table on which are operator 75 15 stands to feed bundles of material to the cutting knives.

An open end hopper 19 formed by side plates 20 secured to the top rails 3, guides the stalk portion of the corn, after the 80 heads are severed, to a belt conveyer 21 located in the bottom of the hopper. The conveyer 21 is mounted at one end on an idle shaft 22 having bearings on the beam 5 and at the other end on a driven shaft 23. 85

Material is delivered from the conveyer 21 on a second conveyer 24 which is adapted to carry the same to a stack or other place of storage. The conveyer 24 is mounted at one end on an idle roller 25 and at the other 90 95 on a driven roller 26.

A conveyer 27 is mounted at the opposite end of the frame 1 from that at which the conveyer 24 is mounted and carries the head portion of the corn to a point of storage. 95 The conveyer is mounted on rollers 28 and 29, the latter being the driven roll.

The conveyers 24 and 27 are mounted in troughs 30, the same being supported at their end adjacent the frame 1 by means 100 of arms 31 secured to the trough and having bifurcated ends 32 which are adapted to engage shafts 33 and 34 on which the rollers 26 and 29 are secured. The outer end of the trough 30 is supported by a jack 105 35 which may be moved toward the frame 1 along the trough to elevate the same as needed.

A shaft 36 mounted for rotation in bearings secured to the frame 1 is provided with 110 a pulley 37. A belt 38 is trained over the pulleys 10 and 37 to impart motion from

the shaft 7 to the shaft 36. Beveled pinions 39 are fixed to the shaft 36 and mesh with beveled gears 40 secured to the shafts 33 and 34.

5 The shafts 23 and 33 are provided with pulleys 41 and 42 respectively and a belt 43 imparts motion from the shaft 33 to drive the conveyer 21, so that when power is applied to the belt wheel 8, the entire mechanism is driven through their respective driving elements. The cutter 11 is rotated at high speed and thereby rotates the cutter 13 severing the heads from grain fed to the machine and carrying the separated parts 10 in opposite directions to be stacked or otherwise disposed of.

In operation, power is applied to the shaft 7 from any suitable source through the belt pulley 8, which causes the cutting disks 11 20 and 13 to rotate, an operator standing on the platform 18 feeds the grain from the table 17 to the cutting knives. The stalks fall on the rotating knives near the head of the grain so that the more valuable head 25 portion is severed from the stalk, close to the head and may be taken care of separately from the stalk.

The carrier 27 being driven from the shaft 34, with its top run moving away from the 30 cutting knives conveys the heads away from the machine to be stacked, stored or otherwise disposed of. The stalks drop on the conveyer 21 which is driven from the shaft 23 through the belt 43. The top run of the 35 conveyer 21 moves toward the rear of the machine carrying the stalk portion and depositing the same on the conveyer 24 which is driven by the shaft 33, the shaft 33 receiving its motion from the shaft 36 through 40 the gears 39 and 40 located at that end of the frame remote from the cutting knives, the stalks are thereby carried to a convenient point and deposited on a stack.

Having thus described the invention what 45 is claimed is:—

1. In a device of the class described, a frame, a cutter, a conveyer mounted beneath the cutter for receiving material therefrom, a second conveyer onto which the first 50 mentioned conveyer discharges and a third conveyer located adjacent the cutter and disposed opposite the first mentioned conveyer, the second and third mentioned conveyers being pivotally and detachably connected to the frame.

2. In a device of the class described, a frame, a cutter comprising a cutting disk rotatably mounted and a pair of concavo-convex disks between which the first mentioned disk rotates, a conveyer mounted for 60 rotation beneath the cutter and means for simultaneously rotating the cutter and conveyer.

3. In a device of the class described, a frame having a hopper, a cutter mounted for operation transversely of the hopper at one end thereof, a conveyer mounted in the bottom of the hopper and adapted to remove material from the cutter, a second conveyer for receiving material from the first mentioned conveyer, a third conveyer located adjacent the cutter on the side thereof opposite the first mentioned conveyer, and means for operating the first and third mentioned conveyers in opposite directions away 70 from the cutter.

4. In a device of the class described, a frame, a cutter comprising a rotatable disk having arcuate cutting teeth said teeth passing between and in contact with a pair of 80 concavo-convex disks, a conveyer mounted on the frame for moving material from the cutter, a second conveyer on which the first mentioned conveyer discharges, means for driving the said conveyers in the same direction, a third conveyer on the opposite side of the cutter from the first mentioned conveyer and means for driving the third conveyer in a direction opposite to that of the first mentioned conveyers. 90

5. In a device of the class described, a frame having an open end hopper, a cutter mounted transversely of the hopper, said cutter comprising a disk mounted for rotation and having arcuate cutting teeth and 95 a pair of concavo-convex disks, also mounted for rotation, the teeth of the first mentioned disk moving between and in contact with the meeting edges of the second mentioned disks and means for conveying material from the cutter in opposite directions therefrom. 100

In testimony that I claim the foregoing as my own, I have hereto affixed my signature in the presence of two witnesses.

WILBUR M. GARRETT.
